UNITED STATES PATENT OFFICE.

CHARLES E. HOOVER, OF STRASBURG, PENNSYLVANIA.

WASHING-MACHINE.

1,099,370.

Specification of Letters Patent.

Patented June 9, 1914.

Application filed October 11, 1912. Serial No. 725,212.

To all whom it may concern:

Be it known that I, CHARLES E. HOOVER, a citizen of the United States, residing at Strasburg, in the county of Lancaster and State of Pennsylvania, have invented certain new and useful Improvements in Washing-Machines; and I do hereby declare the following to be a full, clear, and exact description of the invention, such as will enable others skilled in the art to which it appertains to make and use the same.

This invention relates to improvements in washing machines, one object of the invention being to so construct a washing machine, that it can be operated as a machine of the "pounder" type, or as a machine of the "agitator" type, or as a machine of the "alternating rotary rubber" type.

A further object is to so construct the machine that a rubbing board and agitators may be operated either separately or simultaneously.

A further object is to construct the machine in such manner that all of the operations above mentioned can be accomplished by the same motion of a single power-applying means.

With these and other objects in view, the invention consists in certain novel features of construction and combinations of parts as hereinafter set forth and pointed out in the claims.

In the accompanying drawings, Figure 1 is a sectional view of a washing machine embodying my improvements; Fig. 2 is a sectional view on the line $x-x$ of Fig. 1; Fig. 3 is a sectional view on the line $y-y$ of Fig. 1; Fig. 4 is a sectional view on the line $z-z$ of Fig. 1; Fig. 5 is a plan view; Fig. 6 is a sectional view showing the operating devices connected with the upper rubber board or pounder and agitators; Fig. 7 is a view of said operating devices in elevation, showing the parts adjusted for reciprocating the pounder; Fig. 8 is a plan view of the bottom rubber board; Fig. 9 is a plan view showing the upper rubber board or pounder with the valve in place thereon; Fig. 10 is a detail view of the yielding central member of the lower rubber board, and Fig. 11 is an enlarged detail view showing the bracket or spider which carries the agitator arms.

1 represents a tub provided with a cover 2 hinged at one edge to an inwardly-project-

ing flange 3—a latch device 4 being provided for the free edge of the cover and a loop or handhold 5 is also provided on the cover for raising the latter and the mechanism carried thereby to the position shown in dotted lines in Fig. 1. When the cover and operating mechanism are elevated, they will be sustained in such position so that the water may drain into the tub, by means of a prop 6. This prop is hinged at 7 to the cover and passes freely through a perforated bracket 8 secured to the side of the tub, the free end of said prop being made with a toe 9 which (when the prop is in vertical position as shown in dotted lines, Fig. 1) will rest on a shoulder 10 at the lower end of the bracket 8.

The cover 2 is provided centrally with an enlargement 11 and a tapering hole 12 and over said enlargement, a horizontally disposed gear 13 is located and provided with a depending hub portion 14 which enters the hole 12, anti-friction balls 15 being located between the inner wall of said enlargement and the gear at the juncture of the depending hub portion 14 with the body of the gear. The gear is made with a central angular hole through which two vertical bars 16—17 pass. The lower end of the bar 16 is provided with a threaded shank 18 to enter a threaded socket in the center of an upper rubber board or pounder 19. A collar 20 in the center of a bracket or spider 21, embraces the lower portions of the two bars 16—17 and is securely fastened to the bar 17 by means of a bolt 22. The bracket or spider 21 carries a plurality of agitators 23 which pass through holes 24 in the upper rubber or pounder 19. The central portion of the pounder 19 is made with an upward bulge 25 where it is attached to the bar 16 and the body of said pounder is made with a corrugated under face as shown in Fig. 1 and with several sets of annular series of perforations 26—27—28 which are normally closed by valve rings 29—30—31. These valve rings have free vertical movement to open the perforations in the pounder when the latter is moved downwardly and the rings 29 and 30 are limited in such vertical movement by means of stop arms or lugs 32 secured to the pounder between said valve rings 29—30. The upward movement of the inner valve ring 31 is limited by stop arms 33 projecting from a ring or plate 34 held between the

central bulged portion of the pounder and the shoulder at the upper end of the shank 18 on bar 16.

The upper rubber or pounder 19 is intended to coöperate with a bottom board or rubber 35 located in the bottom of the tub and elevated somewhat from the bottom of the tub by means of feet 36. The bottom board or rubber may be made of sheet metal and is 10 corrugated circumferentially and also radially and is made with several annular series of perforations 37, which may be formed by first making slits and then depressing the metal at one side of each slit, as indicated at 15 Fig. 8. Thus the perforations are located at the sides of the circumferential corrugations of the rubber, so that when the pounder is reciprocated vertically during the operation of the machine (as hereinafter described) the water will be caused to flow in radial streams through the bottom rubber and made to gently but thoroughly penetrate all parts of the mass of clothes disposed between the boards. In order to prevent any of the clothes from becoming disposed centrally between the two boards out of the zone of the active elements of the two boards, I provide a dome 38^a over the center of the lower board. This dome consists of a 20 hollow shell having a plurality of slots 39 and provided with a flanged base portion 40 disposed in a socket member 41. A spring 42 in said socket member, serves to press the dome upwardly to the position shown in 25 Fig. 1. When the machine is in operation, the dome 38 will prevent the clothes collecting centrally between the boards, but as said dome is yieldably supported, it can be depressed by the upper board or pounder (or by 30 the lower end of the bar 16 to which said board or pounder is secured) and thus said upper board or pounder will not be limited by the dome in its downward movements toward the lower board or rubber.

45 My improvements contemplate means for relatively adjusting the pounder and agitators; means for imparting alternating rotary motion to both the pounder and the agitators; means for vertically reciprocating 50 the pounder independently of the agitators or simultaneously therewith, and means for imparting alternating rotary motion to the agitators and simultaneously vertically reciprocating the pounder,—all of said operating means being actuated from the same initial source of power. The mechanism whereby the various results above enumerated may be accomplished, will now be described.

60 The bar 16 to which the upper board or pounder 19 is secured, extends upwardly above the gear 13 and is provided on its inner side with a plurality of projections 43, forming sockets or recesses 44 and the projections 43 are provided with sockets 45.

The bar 17 also extends above the gear 13 and is enlarged as at 46, this enlarged portion being made approximately semi-circular in cross section and provided in its inner flat face with a vertical groove 47 into which the enlarged socketed portion of the bar 16 projects, one of said bars thus constituting a guide for the other. An approximately semi-circular plate 48 loosely embraces that portion of the bar 16 which projects above 75 the gear 13 and is provided with parallel segmental flanges 49. The plate 48 is provided at its upper end with lugs or hooks 50 which serve as bearings for a locking bar 51 adapted to engage in one or another of the recesses 44 of bar 16 and lock the plate 48 to the bar 16 at any desired adjustment. The semi-circular plate 48 and the semi-circular portion 46 of bar 17 coöperate to form a cylindrical structure which passes 80 through and is guided by a ring 52 at the upper end of a standard 53; the base of the latter being provided with flanges 54 secured to the cover 2. The standard 53 is provided near its bottom with a lug 55 which projects sufficiently over the gear 13 to prevent upward displacement of the latter. A locking block 56 is adjustably mounted upon the gear 13 and is adapted to overhang a flange 57 at the base of the enlarged part 46 95 of bar 17 as shown in Fig. 7 to prevent vertical movement of said bar and the agitators attached thereto, or said locking block 56 may be adjusted to the position shown in Fig. 6, to permit vertical movement of the 100 bar 17 and the agitators.

Should it be desired to adjust the upper rubber or pounder 19 relatively to the agitators so that the latter will be caused to project a greater or less distance through or 105 beyond the former, and cause said pounder and agitators to reciprocate vertically together, this may be accomplished by passing a pin 58 transversely through a hole near the upper end of the part 46 and causing it to 110 enter one of the sockets 45 of bar 16.

A bracket 59 is secured upon the cover 2 near the gear 13 and affords a bearing 60 for a shaft 61, a bearing 62 being also provided for said shaft near the periphery of 115 the cover. The shaft 61 is provided at one end with a crank arm 63 carrying a roller 64 disposed between the segmental flanges 49 of plate 48, and to the outer end of said shaft, a wheel 65 is secured. This wheel 120 may be provided with a handle 66 whereby it may be normally operated, or said wheel may be provided with gear teeth 67 to receive motion from a gear 68 to be driven from any suitable motor,—or both manual 125 and power operating means may be provided.

It is apparent that the rotation of the shaft 61 will cause vertical reciprocation of the plate 48 and that if said plate be coupled 130

to the bar 16 by means of the locking bar 51, said bar 16 and the upper board or pounder will also be reciprocated vertically causing said pounder to alternately apply pressure to the clothes between the two boards and to relieve such pressure, and at the same time to cause a circulation of water through and among the clothes which will effectually clean them.

10 A shaft 69 is mounted in suitable bearings 70 on the cover 2 and carries a rack bar 71 adapted to mesh with the gear 13. The shaft 69 is provided at one end with an arm 72 (disposed at right angles thereto) and to this arm, one end of a pitman 73 is pivotally attached the other end of the pitman 73 being pivotally and removably attached (by means of a latch device 74,) to a crank arm 75 of the shaft 61. By means of this construction, 20 rotation of the shaft 61 will cause reciprocation of the shaft 69 and the rack bar 71 carried thereby, and motion will be transmitted by the rack bar to the gear 13 to oscillate the latter, thus imparting an oscillatory motion to the agitators. Such oscillatory motion will also be imparted to the upper rubber or pounder and the clothes will be agitated between the two boards 19 and 35, and the clothes will also be rubbed by reason of 30 the opposing corrugated faces of the two boards or rubbers.

If the mechanism is connected as shown in full lines in Fig. 1, and the parts are adjusted as shown in Fig. 6; operation of the 35 shaft 61 will cause alternating rotary motion of both the upper board or pounder and also the agitators, and simultaneously with this operation, the upper board or pounder will be reciprocated vertically.

40 Should it be desired to operate the upper board as a pounder only; viz. to reciprocate said upper board vertically without imparting alternating rotary motion to it and without imparting such motion to the agitators, 45 the parts 46 and 48 will be disconnected by removing the pin 58 and the locking block 56 will be moved to the position shown in Fig. 7, to overhang the flange 57 and thus prevent vertical movement of the bar. The 50 operator will also disconnect the pitman 73 from the crank arm 75 and then partially rotate said shaft to cause a tooth 76 thereon to engage the gear 13 and prevent it from rotating. When the shaft 69 has been thus 55 partially rotated, the pitman will lie upon the cover 2 as shown in dotted lines in Fig. 5 (where it may be held by a clip 77) and the arm 72 will lie in a horizontal position adjacent to a stop pin 78 on the cover 2. 60 The mechanism for imparting alternating rotary motion to the pounder and agitators will now have been disconnected and locked, and the operation of the shaft 61 will cause only the vertical reciprocation of the upper 65 board or pounder 19.

Having fully described my invention what I claim as new and desire to secure by Letters-Patent, is:—

1. In a washing machine, the combination with a tub, of a corrugated pounder board, 70 operating means for imparting alternating rotary motion to said pounder board, other operating means for reciprocating said pounder board vertically, and means for detachably connecting said operating means, 75 whereby they may be actuated simultaneously or separately.

2. In a washing machine, the combination with a tub, of a sheet metal bottom rubber board having circumferential and also radial 80 corrugations, said rubber board having openings in portions of the radial corrugations which form parts of the circumferential corrugations, a pounder board having perforations, upwardly opening valves for said perforations, and means for vertically reciprocating said pounder board.

3. In a washing machine, the combination with a tub provided with a cover, of a corrugated pounder board, agitators passing through the same, bars passing through the cover and secured respectively to said pounder board and agitators, a gear for rotating said bars, an operating shaft having two crank arms, connections between one 90 of said crank arms and the gear for imparting alternating rotary motion to the latter, and connections between the other crank arm and one of said bars for vertically reciprocating the pounder board.

4. In a washing machine, the combination with a tub and a cover therefor, of a pounder board, agitators, bars connected respectively with the pounder board and the agitators, means for adjustably coupling 105 said bars, and means for reciprocating said bars.

5. In a washing machine, the combination with a tub and a cover therefor, of a pounder board, agitators, bars connected respectively 110 with the pounder board and agitators and passing through the cover, means for reciprocating the bar which is connected with the pounder board, operating means for imparting alternating rotary motion to the 115 bar which is connected with the agitators, and means for locking said operating means.

6. In a washing machine, the combination with a tub and a cover therefor, of two bars passing through the cover, a pounder 120 board secured to one of said bars, agitators carried by the other bar, a gear connected with said bars, a locking block adjustably mounted on said gear, a flange on the agitator bar and adapted to coöperate with said locking block, means for imparting alternating rotary motion to said bars, and means for reciprocating the bar of the pounder board.

7. In a washing machine, the combina- 130

tion with a tub and a cover therefor, of a gear mounted on said cover, two bars passing freely through said gear and rotatable therewith, agitators connected with one of 5 said bars, a pounder board connected with the other bar, said last-mentioned bar having a series of notches a plate embracing said last-mentioned bar, a locking bar mounted on said plate and adapted to enter 10 a notch of the notched bar for coupling the latter to said plate, parallel segmental flanges on said plate, an operating shaft, and a crank arm on said shaft to enter between said parallel segmental flanges, where- 15 by the pounder board may be reciprocated, and means for imparting alternating rotary motion to said gear to alternately rotate the pounder board and the agitators.

8. In a washing machine, the combina- 20 tion with a tub and a cover therefor, of a gear mounted on the cover, two bars passing through said gear and rotatable therewith, one of said bars having an enlarged part above the gear, said enlarged part having 25 a vertical groove in its inner face, the other bar having a portion entering said groove and provided with a plurality of sockets, means for coupling said enlarged portion of one of the bars with the socketed portion of 30 the other bar, agitators secured to one of said bars, a pounder board secured to the other bar, means for imparting alternately rotary motion to said gear, and means connected with the socketed bar for reciprocating the same.

9. In a washing machine, the combina- 35 tion with a tub and a cover therefor, of a

gear mounted on said cover, two bars passing through said gear and rotatable therewith, agitators carried by one of said bars, a pounder board secured to the other bar, a crank shaft operatively connected with the last-mentioned bar for reciprocating it, a shaft mounted on the cover and provided with a rack bar to mesh with the gear, a tooth on said shaft to engage the gear when the shaft is rocked, for locking said gear, an arm secured to said shaft, a pitman pivoted at one end to said arm, and means removably connecting the other end of said pitman with a crank of said crank shaft.

10. In a washing machine, the combina- 45 tion with a tub and a pounder board having a raised central portion, of a bottom board, and a yieldable dome located in the center 50 of said bottom board and adapted to engage the under face of the pounder board in the raised central part thereof.

11. In a washing machine, the combina- 55 tion with a tub and a corrugated pounder 60 board, of a corrugated bottom board, a per- forated vertically movable dome rising above the bottom board under the center of the pounder board, and a spring normally press- ing said dome upwardly toward the bottom 65 of the pounder board.

In testimony whereof, I have signed this specification in the presence of two sub- scribing witnesses.

CHARLES E. HOOVER.
